UNITED STATES PATENT OFFICE.

HERMAN L. HEINE, OF CHICAGO, ILLINOIS.

DESIGN FOR A LAP-LAST.

SPECIFICATION forming part of Design No. 22,289, dated March 14, 1893.

Application filed January 24, 1893. Serial No. 459,604. Term of patent 7 years.

To all whom it may concern:

Be it known that I, HERMAN L. HEINE, a citizen of the United States, residing at Chicago, in the county of Cook and State of Illinois, have invented and produced a new and original Design for Lap-Lasts, of which the following is a specification, reference being had to the accompanying drawings, which are made a part hereof, and in which—

5 Figure 1 is a plan view of a last embodying the new design. Fig. 2 is a side elevation thereof. Figs. 3 and 4 are transverse sections thereof on the lines 3—3 and 4—4, respectively.

10 A last of the new design comprises the two foot portions A and A' united by a shank B, the toes being at the extremities of the last and the soles being upon opposite sides thereof—one presented upward and the other 15 downward. In side elevation the top side, and also the bottom side of the last present an outline that follows the course of a compound curve. Upon opposite sides of a line drawn transversely through the center of the 20 shank B, the two foot portions A and A' are alike, so that the following description of the 25 essential and characteristic features of the

new design refers to only one of them, similar parts of both being indicated by similar letters, the prime mark being added to the letters used on the portion A', for the sake of distinction. The top side of the portion A, as seen in transverse section, is formed upon curves C which decrease in radius from the toe to the instep, as shown by Figs. 3 and 4. 30 The outline of the portion A, as seen in plan view, comprises the curve D—D at the toe, curves of greater radii extending rearward from D, D, to E, E, and the curves of less radii than these latter curves extending from 35 E, E, to F, F. The sides of the shank are formed on hollow curves G, G. The surface of the sole has its outer edge beveled off as shown at H, and it has also a mount or raised portion I, and a slight depression J lying next 40 to it and extending lengthwise.

What I claim as new, and desire to secure by Letters Patent, is—

The design for lap lasts, substantially as herein shown and described.

HERMAN L. HEINE.
